Filed Feb. 12, 1958, Ser. No. 49,614

Term of patent 14 years

(Cl. D33—14)

Fig. 1 is a perspective view of a table illustrating at its dominant feature the combined table leg and brace shown in full lines;

Fig. 2 is a front-on elevational view of the same; and

Fig. 3 is a side elevational view of the same rotated approximately 90° from the view of Fig. 2.

My design has as its dominant feature the combined table leg and brace as shown in full lines in Figs. 1, 2 and 3.

I claim:

The ornamental design for a table, substantially as shown and described.
